UNITED STATES PATENT OFFICE

156,845

FRUIT AND VEGETABLE SLICER

Mark Ross, Los Angeles, Calif.

Application September 18, 1948, Serial No. 148,650

Term of patent 7 years

(Cl. D89—1)

To all whom it may concern:

Be it known that I, Mark Ross, a citizen of the United States of America and a resident of the city of Los Angeles, in the State of California, have invented a new, original, and ornamental Design for a Fruit and Vegetable Slicer, of which the following is a specification, reference being had to the accompanying drawing, forming a part thereof.

In the drawings:

Figure 1 is a side elevational view of the fruit and vegetable slicer, showing my new design,

Figure 2 is a plan view thereof,

Figure 3 is an end elevational view thereof,

Figure 4 is the opposite end elevational view thereof, and

Figure 5 is a view taken substantially along line 5—5 of Figure 1.

I claim:

The ornamental design for a fruit and vegetable slicer, substantially as shown.

MARK ROSS.
